PUMP

H. Hix Wolfe and Edward W. Haas, Dayton, Ohio,
assignors to The Dayton Pump and Mfg. Company,
Dayton, Ohio, a corporation of Ohio

Application November 21, 1947, Serial No. 787,298

3 Claims. (Cl. 103—5)

1

The present invention deals with water pumps and is concerned primarily with a pump of the type which is readily adaptable for use with either shallow or deep wells.

A pump of the type with which this invention is concerned comprises generally a main casing that houses an impeller, an air separating chamber, together with a jet device which in cooperation with the other elements, creates a partial vacuum that is effective on a suction pipe that is connected to the casing. This jet device is employed when the pump is used on a shallow well, but removed when the pump is used on a deep well. The casing is formed with an opening in alignment with the jet device and this opening permits removal and positioning of the jet device. When the pump is being used on a shallow well, this opening is closed by a plug, but when used on a deep well, a pressure or drive pipe is connected thereto.

While pumps of this general type are now meeting with an appreciable degree of usage, the now known pumps have certain short-comings which are intended to be obviated by the present invention. Among these may be noted that the presently known pumps generally include a single impeller which is ordinarily of the centrifugal type. The present invention recognizes that in many instances, a single impeller will not be sufficient to supply the pressure required. Accordingly, a highly important object of the present invention lies in the provision of a pump assembly of the character above indicated, which is particularly adapted to enclose either one or a plurality of impeller elements.

In achieving this object, a casing for each impeller is provided. This casing is divided into two complementary parts.

Another highly important object of the invention is the provision in a pump assembly, of the character above indicated, of an impeller assembly that includes a plurality of impeller casings with one part of one casing being formed integrally with another part of another casing. With such an arrangement, two or as many impeller cases as may be required, may be assembled in the pump as an entirety.

Yet another object of the invention is the provision of a new and improved way of mounting the impeller casing in the pump assembly. In accordance with this invention, the impeller casings are first assembled with the innermost part of the inner casing being bolted to the outermost part of the outer casing and with any in-

2

termediate casing parts clamped therebetween. The outermost casing part is then bolted to the end plate of the pump assembly, whereupon, the latter element is in turn bolted to the main pump casing. Such an arrangement presents the advantage of readily assembling as many impeller units as may be required in the main pump assembly.

When a pump, of the type with which this invention is concerned, is employed in connection with a deep well, a drive pipe is connected to the air separating chamber of the pump casing. With the devices heretofore employed, there has not been any effective way for controlling or regulating the pressure of water which is supplied to this drive pipe. With this condition in mind, a further object of the invention, is the provision, in a pump assembly of the type above noted, of means for regulating the pressure of water that is supplied to the drive pipe.

When the jet device is employed for shallow well purposes, it is highly important that it operate with a high degree of efficiency so as to create a suction to the maximum degree possible. With this thought in view, a further object of the invention lies in the provision in a pump, of the type aforesaid, of a pump casing that is provided with a suction pipe inlet together with means of connection from said inlet directly to the venturi of the jet device. By closely positioning the suction inlet with respect to the venturi, maximum efficiency is achieved.

Yet another object of the invention is the provision of a new and improved pump casing which is readily adapted to the change from shallow to deep well pumps and which is designed to operate with maximum efficiency under both conditions of usage.

Various other and more detailed objects and advantages of the invention such as arise in connection with carrying out the above noted ideas in a practical embodiment will in part become apparent and in part be hereinafter stated as the description of the invention proceeds.

The invention therefore, comprises a pump of the type that is adapted for either shallow or deep well use and which is characterized as being readily adapted to contain either one, or a plurality of impellers. Provision is made for regulating the pressure of water that is supplied to the drive pipe, and the various elements are assembled for maximum efficiency in operation.

For a full and more complete understanding 55 of the invention, reference may be had to the

following description and accompanying drawings wherein;

Figure 1 is a fragmentary perspective showing the pump in this invention as mounted on a water tank for shallow well use.

Figure 2 is a perspective comparable to Figure 1, bringing out the arrangement when the pump is employed in conjunction with a deep well.

Figure 3 is a vertical section through the main pump casing and parts housed therein. This view is taken about on the plane represented by the line 3—3 of Figure 1.

Figure 4 is a section through the pump casing taken on a plane normal to the showing of Figure 3. This view is taken about on the plane represented by the lines 4—4 of Figure 3.

Figure 5 is a sectional view comparable to Figure 4 and is taken about on the plane represented by the line 5—5 of Figure 3.

Figure 6 is a sectional view through one end of the pump casing when the latter is adapted for deep well use. This view is taken about on the plane represented by the line 6—6 of Figure 2.

Figure 7 is a detailed view in end elevation of the jet device per se.

Figure 8 is an enlarged detailed sectional view through the jet device per se.

Figure 9 is a view in end elevation of the fitting which is employed to adapt the pump casing to deep well use.

Figure 10 is a view in side elevation of the fitting shown in Figure 9.

Figure 11 is a longitudinal section through the impeller casing being taken about on the plane represented by the line 11—11 of Figure 5; and

Figure 12 is another longitudinal section through the impeller casing being taken about on the plane represented by the line 12—12 of Figure 5.

Referring now to the drawings wherein like reference characters denote corresponding parts and first more particularly to Figure 1, a tank is illustrated at 10. This tank is intended to receive the water that is pumped from the well by the pumping mechanism of this invention. The tank 10 is shown as having feet 11 which are secured to an appropriate support, such as the platform illustrated at 12, by bolts 13.

Welded to the upper portion of the tank 10 are a pair of brackets 14 which preferably are of the angle bar construction illustrated. Resting on the brackets 14 are feet 15 of a main casting 16 which constitutes an essential part of the pump assembly. Bolts shown at 17 anchor the feet 15 to the brackets 14.

The main casting 16 is formed at one end with a thickened cylindrical wall 18. This wall is formed with a threaded opening at 19 and a second threaded opening at 20 which is substantially diametrically opposite to the opening 19. When the pump is used for shallow well purposes, a plug 21 closes the opening 19.

The casting 16 is formed with an end wall 22 which is integrally joined to the thickened wall structure 18 by a circular wall 23. The end wall 22, wall 23 and thickened cylindrical wall 18, together define a main air separating chamber designated 24. A passageway 25 is defined by a conduit structure 26 which preferably is cast integral with the casting 16. This conduit structure 26 is formed with an opening at 27 which establishes communication between the chamber 24 and passageway 25. The passageway 25 includes a central circular part 28 that extends

around a hub 29 that is formed integral with the conduit structure 26.

An inlet or suction chamber 30 is shown as being defined by a circular web 31 that is integral with the casing and which includes a reduced neck as shown at 32. A sleeve 33 integrally joins this reduced neck 32 to the hub 29. At the bottom, a support 34, integrally joins the sleeve 33 to the wall 23.

That portion of the wall 23 immediately above the suction chamber 30 is thickened and provided with a threaded opening 35 into which is screwed a fitting 36 that is connected to a suction pipe 37 by elbows 38 and 39 and a conduit 40.

The hub 29 is formed with a circular opening 41 that is co-axial with the main axis of the pump. The sleeve 33 carries an inwardly extending flange 42 formed with an opening 43 that is coaxial with the opening 41. The reduced neck 32 of the suction chamber provides a flat wall 44 having an opening 45 that is in alignment and coaxial with the openings 41 and 43. The end wall 22 is formed with an opening 46 that is in alignment and coaxial with the openings 41, 43, and 45.

A jet assembly is referred to in its entirety by the reference character J. This jet assembly J is shown in detail in Figures 7 and 8 and as illustrated in Figure 3 may be assembled within the main pump casting with various elements fitting into the openings 41, 43, 45, and 46. This assembly J comprises a carrier plug 47 that is snugly fitted within the opening 46. The plug 47 has a head 48 which may be fastened to the end wall 22 by bolts 49 which pass through openings formed on side extensions of the head 48.

The plug 47 carries a cage 50 which in turn, carries a ring 51. Extending inwardly from the ring 51, is a second cage 52 which at its inner end carries an internally threaded ring 53. A Venturi tube 54 has one end screwed into the ring 53 and its free end is positioned within the opening 41 from which it is slightly spaced. A jet nozzle 55 has its base anchored to the ring 51 and its mouth positioned at the open end of the Venturi tube 54.

When the pump is to be used for shallow well purposes, the jet assembly J is positioned within the main casting 16 in the manner depicted in Figure 3. In this position, the carrier plug 47 closes the opening 46, the ring 51 extends into the opening 45, and packing shown at 56 may be employed to seal this connection. The cage 52 extends across the constricted neck 32 and the ring 53 is snugly fitted in the opening 43.

The Venturi tube 54 is spaced from the extension 33 and extends there-across to the opening 41. It will be noted that the cage 50 bridges the gap between the end wall 22 and the wall 44.

Under normal conditions of usage, the opening 20 communicates with the tank 10 through the medium of the conduit shown at 57. Thus, communication between the passageway 25 and the tank 10 is established.

The impeller assembly is referred to in its entirety by the reference character P. This assembly P will include as many impeller casings as there are impellers. In the form of the invention illustrated in the drawings, two impellers are shown as included in the assembly. Obviously, this number may be varied without departing from the spirit of the invention.

The inner impeller casing, that is the one which is housed within the ring 18, comprises two complementary parts 58 and 59. The outer impeller

casing is made up of the complementary parts 60 and 61. It is notable, that the casing part 59 of the inner impeller casing is integrally connected to the casing part 60 of the outer impeller casing. A pressure chamber 62 is defined by the outer casing part 61 and wall structure 63 that is formed integrally therewith. The unit made up of the casing parts 59 and 60 together define an intermediate chamber 64.

The inner impeller casing that is made up of the parts 58 and 59 together define outer volutes 65 which communicate with the intermediate chamber 64 through the medium of passages 66. Likewise, the outer impeller, made up of the parts 60 and 61, include outer volutes corresponding to the volutes 65 and which communicate with the pressure chamber 62 through the medium of passages corresponding to the passages 66. The several impeller casing parts 58, 59, 60, and 61 are formed with aligned openings which together define passages 67 that establish communication between the pressure chamber 62 and the air separating chamber 24. Screw bolts shown at 9 serve to maintain the several impeller casing parts in assembled relation. These bolts 9 extend from the inner part 58 of the inner impeller casing, to the outer part 61 of the outer impeller casing.

The unit, made up of the impeller casing part 61 and wall structure 63, which is the unit defining the pressure chamber 62, is anchored to an end plate 68 by screw bolts shown at 69. This end plate 68, is in turn, anchored to the main casting 16 by bolts shown at 17. A motor is depicted somewhat diagrammatically at 71 and this motor is anchored to the end plate 68 as indicated at 12. The motor 71 includes a main drive shaft 73 which is driven by the motor in a well known manner.

The unit 61-63 is formed with a hub 74 in which the shaft 73 is journalled. A fluid seal, which is referred to in its entirety by the reference character S, is mounted about the shaft 73 within the unit 61-63 and serves to prevent water leaking along the shaft 73. A centrifugal impeller 75 is keyed to the shaft 73 so as to be driven thereby, and is positioned within the outer impeller casing made up of the parts 60 and 61. This impeller 75 includes a mouth or inlet 76 that communicates with the chamber 64. The impeller 75 is of a construction well known in this art, and the particular details thereof, are not a part of this invention. It suffices to point out, that passages 77 establish communication between the inlet 76 and the volutes 65 in the casing.

The shaft 73 extends inwardly through the mouth 76 and its inner end is journalled in the casing part 59 as by the bearing shown at 78. A second impeller 79 is anchored to the inner end of the shaft 73 so as to rotate therewith. This impeller 79 is positioned within the inner impeller casing made up of the parts 58 and 59. The impeller 79 is formed with an inlet tube 80 that extends through the casing part 58 to a point immediately contiguous to the hub 29. A ring 81 is positioned around the tube 80 and an expansion seal 82 is carried by this ring 81 and is interposed between the hub 29 and casing part 58.

Shallow well operation

The condition of the pump for shallow well operation is well brought out in Figures 1 and 3. It is important to note that only the suction pipe

37 extends down into the shallow well and the opening 46 is closed by the carrier plug 47. When the motor 71 is brought into operation to rotate the shaft 73, the latter in turn, rotates the impellers 75 and 79. Pressure of the water is built up through successive stages. Thus, water coming in through the inlet tube 80, is thrown outwardly by the impeller 79 to the volutes 65. From the volutes 65, the water under increased pressure passes through the opening 66 to the chamber 64. From there, the water passes through the inlet 76 through passages 77 of the impeller 75 and thence outwardly to the volutes 65 of the impeller casings 60-61. The water under increased pressure, then passes into the pressure chamber 62 through the opening 66. From the chamber 62, the water is passed back into the air separating chamber 24 through the passages 67. This water which is under increased pressure, now is broken up into divided streams. Part of the water passes through the jet nozzle 55 into the Venturi tube 54, and in so passing, creates a partial vacuum or suction in the suction chamber 30. This draws water up from the well to the suction pipe 37. At the same time, another part of the water passes through the opening 27 into the passageway 25 and thence through the opening 20 to the tank 10.

When the pump is used as a shallow well pump the pressure regulating valve V is not usually necessary. However, there are instances of shallow well operation wherein the pump is working at a limit of its depth as a shallow well pump, and yet the installer does not wish to go to the expense of the deep well set up. In this instance the pressure regulating valve V can be used to close the passage or opening 27 between the air separating chamber 24 and the discharge passage 25 from the pump to secure an increased pressure in the air separating chamber for increased movement of liquid through the pump injector J and thereby obtain the same degree of extension of the depth of the well at which the pump can operate satisfactorily as a shallow well pump.

Deep well mechanism

When the pump is to be used for deep well purposes, two essential changes are made in the pump mechanism above described. The plug 21 is removed and replaced by a pressure regulating valve such as shown in Figure 6, and referred to in its entirety by the reference character V. The jet assembly J is also removed as an entirety, and replaced by a fitting that is identified in its entirety by the reference character F. This fitting F is shown assembled in Figure 6 and is illustrated in detail in Figures 9 and 10.

The fitting F comprises an elbow 83 which is connected to a drive pipe 84 by coupling elements 85, 86, and 87. The elbow 83 is formed with an annular flange 88 that is adapted to engage the thickened part of the end wall 22 about the opening 46. This flange 88 is formed with ears 89 which are adapted to be bolted to the end wall 22 in exactly the same way as is the head 48 of the carrier plug.

Extending inwardly from the flange 88 is a neck 90 which is snugly fitted in the opening 46. Extending inwardly from this neck 90 is a cage 91 that carries a closure plate 92 that is snugly received in the opening 45. A packing shown at 93 may be employed to effectively secure this joint.

As brought out in Figure 2, the drive pipe 84 and suction pipe 87 extend downwardly into the

well and their lower ends are joined by a Y coupling 94.

It is deemed unnecessary to here enter into a detailed discussion of the pressure regulating valve V. It suffices to point out, that this valve includes a sleeve 95 that is threaded into the opening 19. A valve member 96 is adapted to cooperate with the opening 27 and is carried by a piston 97 that is reciprocally mounted in the sleeve 95. A spring 98 yieldably urges the piston 97 downwardly and normally maintains the valve 96 in seated or closed position with respect to the opening 27. Effective pressure of the spring 98 may be adjusted by adjusting the position of the spring follower 99 that is carried by the sleeve 95.

Deep well operation

In describing the deep well operation, it is believed unnecessary to repeat a description of the operation of the impeller mechanism. It suffices to point out that water under pressure is delivered to the chamber 24 by the impeller assembly. This water under pressure is forced downwardly through the drive pipe 84 to the coupling 94 whereupon, water from the deep well is entrained and forced upwardly through the suction pipe 37. Water from the suction pipe 37 is delivered to the suction chamber 38 and thence through the constricted neck 32, extension 33, and hub 29 to the inlet 80 of the inner impeller.

When pressure of water in the chamber 24 is substantially great, the valve member 96 is unseated, whereupon, water is permitted to flow through the opening 27 into the passageway 25 and thence to the tank 10.

While a preferred specific embodiment of the invention is hereinbefore set forth, it is to be clearly understood that the invention is not to be limited to the exact constructions illustrated and described because various modifications of these details may be provided in putting the invention into practice within the purview of the appended claims.

What is claimed is:

1. In a combination jet-centrifugal pump the combination of, a first casting wall having a hollow central sleeve extending longitudinally therethrough, said sleeve having an opening at both ends thereof, said wall and sleeve defining therebetween an air separating chamber, an impeller assembly removably secured to said casting wall and having a central shaft coaxial with said sleeve, said impeller having a low pressure inlet eye communicating with the opening in said sleeve at one end thereof and a high pressure outlet chamber, said outlet chamber being connected to said air separating chamber by an elongated passage, said passage extending throughout the length of said assembly and being substantially parallel to said shaft, a second wall means within said chamber forming a passage for connecting said air separating chamber with a fluid reservoir, an orifice in said wall means connecting said air separating chamber with the last-mentioned passage, said first casting wall having an opening therein axially aligned with said orifice, a pressure regulating valve in said opening with the valve element thereof comprising means for closing said orifice, an inlet chamber including a third wall means communicating with the opening in said sleeve at the opposite end from said inlet eye, said third wall means separating said inlet chamber from said air separating chamber, a suction pipe connected to said inlet chamber for extension into a well, a jet

assembly including a jet nozzle and Venturi tube positioned in said suction pipe for drawing water upwardly in said suction pipe, and a passageway connecting said air separating chamber to said jet nozzle for forcing water under pressure into said nozzle.

2. In a combination centrifugal pump adapted for either shallow well or deep well use, the combination of, a first casting wall having a hollow central sleeve extending therethrough, said sleeve having an opening at both ends thereof, said wall and sleeve defining an air separating chamber therebetween, an impeller assembly removably attached at one side of said separating chamber and having an inlet eye connected to one opening of said sleeve, said impeller assembly having an outlet pressure chamber, an elongated passage connecting said pressure chamber with said air separating chamber for delivery of fluid under pressure thereto, second wall means within said air separating chamber forming a second passage for connecting said last-mentioned chamber with a fluid reservoir, a first aperture in said second wall means connecting said air separating chamber with said second passage, and a second aperture in said first casting wall axially aligned with said first aperture and receiving a pressure regulating valve with the valve element thereof comprising means for opening and closing said first aperture, an inlet chamber including a third wall means communicating with the other opening in said sleeve and having a suction pipe connected thereto, said third wall means separating said inlet chamber from said air separating chamber, said pipe adapted for extension into a well, said first casting wall including an end wall forming a closure for said air separating chamber and said inlet chamber and an opening in said end wall in alignment with the openings in said sleeve, a flat wall extending inwardly from said end wall and joining said third wall.

3. In a combination centrifugal pump adapted for either shallow well or deep well use, the combination of, a first casting wall having a hollow central sleeve extending therethrough, said sleeve having an opening at both ends thereof, said wall and sleeve defining an air separating chamber therebetween, an impeller assembly removably attached at one side of said separating chamber and having an inlet eye connected to one opening of said sleeve, said impeller assembly having an outlet pressure chamber, an elongated passage connecting said pressure chamber with said air separating chamber for delivery of fluid under pressure thereto, second wall means within said air separating chamber forming a second passage for connecting said last-mentioned chamber with a fluid reservoir, a first aperture in said second wall means connecting said air separating chamber with said second passage, an inlet chamber including a third wall means communicating with the other opening in said sleeve and having a suction pipe connected thereto, said third wall means separating said inlet chamber from said air separating chamber, said pipe adapted for extension into a well, said first casting wall including an end wall forming a closure for said air separating chamber and said inlet chamber and an opening in said end wall in alignment with the openings in said sleeve, a flat wall extending inwardly from said end wall and joining said third wall.
